US0D1073338S

(12) **United States Design Patent** (10) Patent No.: **US D1,073,338 S**
(45) Date of Patent: ** May 6, 2025

(54) **STREET BENCH**

(71) Applicant: **Norbert Roztocki**, Dornach (CH)

(72) Inventor: **Norbert Roztocki**, Dornach (CH)

(73) Assignee: **Norbert Roztocki**, Dornach (CH)

(**) Term: **15 Years**

(21) Appl. No.: **35/519,094**

(22) Filed: **Oct. 22, 2023**

(80) **Hague Agreement Data**

Int. Filing Date: **Oct. 22, 2023**

Int. Reg. No.: **DM/233095**

Int. Reg. Date: **Oct. 22, 2023**

Int. Reg. Pub. Date: **Nov. 24, 2023**

(51) **LOC (15) Cl.** **06-01**

(52) **U.S. Cl.**

USPC **D6/349**; D21/826

(58) **Field of Classification Search**

USPC D6/335, 349, 361, 368, 370, 381, 691,

D6/708; D21/826; D30/160

CPC A47C 4/022; A47C 4/025; A47C 4/03;

A63B 9/00
